UNITED STATES PATENT OFFICE

2,278,398

MIXING DEVICE

Joseph H. Wittmann, Los Angeles, Calif.

Application October 11, 1940, Serial No. 360,759

5 Claims. (Cl. 259—128)

This invention relates to mixing devices, particularly adapted for whipping cream, mixing liquids, or mixing liquids with various ingredients, and has for its principal object to provide a device of this character with flexible mixing elements that remain alive and active so as to scrape up every particle of settling ingredients and thereby provide an exceptionally effective and efficient mixer.

Other objects of the invention are to provide a simple and inexpensive construction capable of easy manufacture and assembly; to provide a mixer that is self-cleaning and extremely sanitary; to provide flexible mixing elements consisting of a plurality of convolutions designed to avoid interlock of one convolution into another; and to provide a mixer with agitating elements that are self-adjustable relatively to the bottom of a container so that the elements operate in close contact therewith.

In accomplishing these and other objects of the invention, as hereinafter pointed out, I have provided improved details of structure, the preferred forms of which are illustrated in the accompanying drawing, wherein:

Fig. 1 is a perspective view of a mixing device constructed in accordance with the present invention and showing contact of the mixing elements with the bottom of a mixing bowl.

Fig. 2 is a detail perspective view of the flexible mixing elements with the hooked ends thereof brought together and ready to be connected with the operating shaft.

Fig. 3 is a perspective view of one of the mixing elements in relaxed condition showing the form of the convolutions.

Fig. 4 is a detail sectional view through the handle, particularly illustrating the nut-like bearing for engaging the spiral section of the operating shaft.

Fig. 5 is a detail perspective view of the lower portion of the handle, nut-like bearing, upper portion of the operating shaft, and the bearing retaining caps, in disassembled spaced relation.

Referring more in detail to the drawing:

1 designates a mixing device constructed in accordance with the present invention and which includes an operating shaft 2, mixing or agitating elements 3 and 4, and a handle 5.

The operating shaft includes a relatively rigid, rod-like body 6 terminating at the lower end in a flattened head 7 forming lateral wings 8 and 9 having spaced apertures 10 and 11 therein. The lower portions of the wings terminate in a ball-shaped step-bearing 12 on which the shaft is adapted for rotary support by the bottom of a mixing vessel. The upper portion of the shaft is shaped to provide a flat, spiral thread 13, to engage in a slot-like opening 14 of a nut-like bearing disk 15. Above the spiral thread 13 the

shaft has a collar-like washer 16 supported on ears 17 struck from the metal of the shaft, leaving a pintle 18 above the collar.

The handle 5 has a shank 19 provided with an axial bore 20 in which is inserted a metallic tube 21 forming a housing for a coil spring 22, one end of which seats against the bottom 23 of the bore 20 and its opposite end engages over the pintle 18 and seats against the washer-like collar 16 of the shaft when the shaft is inserted in the handle.

The washer-like bearing 15 is retained in abutting relation with the tube by a cap 24 having a socket 25 of suitable diameter to snugly receive the part 15 and to engage over the shank of the handle, as clearly shown in Fig. 4, the cap being secured to the shank by any suitable means such as a plastic cement.

The upper portion of the handle is in the form of a knob 26 adapted to be engaged by the fingers or palm of the hand to exert a downward pressure on the handle whereby the bearing 15 moves over the convolutions of the spiral thread to effect rotation of the shaft on the ball-like step-bearing 12, as later described.

The mixing or agitating elements 3 and 4 are formed of a flexible wire-like material of resilient character and wound into helical form to provide a plurality of convolutions 27 increasing in diameter from one end toward the center convolution and then decreasing toward the other end to form a substantially barrel-shape when the formed element is in relaxed condition as shown in Fig. 3. The endmost convolutions terminate in hooks 28 and 29 to engage in the apertures 10 and 11. To engage the hooks in the apertures, the hooked ends are brought together to impart a curve in the axis of the helix, whereby the convolution at one end is adapted to extend substantially horizontally relative to the shaft while the convolution at the opposite end extends substantially parallel with the shaft as shown in Figs. 1 and 2. The convolutions are thus placed in compression on the attached sides and bulge outwardly on the other to provide extended contact with the material to be mixed.

When the mixing elements are attached to the head of the shaft, the intermediate convolutions are free to flex independently of each other, and the endmost convolutions hinge within the apertures 10 and 11 so that the elements automatically adjust themselves to the bottom of a mixing bowl or like vessel with which the mixing device is used. Attention is also called to the fact that the centers of gravity or greater mass of weight are above the pivotal connections, and therefore centrifugal action causes the bottom convolutions to scrape on the bottom of the mixing vessel.

In using the mixing device, it is inserted within the mixing bowl so that the step-bearing 12

engages the bottom of the bowl and pressure is applied on the handle 5 to compress the spring 22, causing the shank thereof to move downwardly over the spiral, carrying the nut-like bearing 15 therewith. Since the handle is retained from rotation, the sides of the slot engaging the faces of the spiral produce rotation of the shaft in one direction and the mixing elements are gyrated therewith. The centrifugal force and the flexible, spring-like character of the convolutions automatically retain the mixing elements in scraping contact with the bottom of the bowl so that settling particles are scraped from the bottom and mixed with the liquid. Upon release of pressure on the handle, the spring returns the handle to its original position, and the nut-like bearing rotates the shaft in the opposite direction. Thus by providing a reciprocating action to the handle, the agitating elements gyrate first in one direction and then in the other direction, the number of rotations between changes in direction depending upon the stroke of the handle and the number of convolutions in the spiral.

The mixing elements, being formed of relatively thin material, remain alive and active during the entire operation thereof to thoroughly scrape up the particles and effect a quick and easy mixture of the materials.

Attention is directed to the fact that the tension produced incidental to common anchorage of the ends of the helix retains the convolutions in extended position and at varying angles with respect to the bottom of the vessel so that the angle of attack for each convolution is different and effects thorough agitation of the material so that unmixed or unwhipped liquid is not left in the bottom of the bowl.

The flexible character of the agitating or mixing elements permits folding thereof against the side of the shaft so that the entire device is readily packaged in a relatively small tube-like container (not shown). Upon release from the container, the convolutions readily return to their normal position as shown in Fig. 1.

From the foregoing it is obvious that I have provided a mixing device that is of simple, inexpensive construction and which is well adapted for mixing various ingredients with liquids or for whipping cream, beating eggs, and otherwise acting upon similar material.

What I claim and desire to secure by Letters Patent is:

1. A mixing device including, a rotatable shaft having an end for engaging the bottom of a vessel and provided with laterally extending wings, and flexible agitating elements each including a helical wire-like form normally consisting of a series of coaxial convolutions with the terminals of the end convolutions brought together and pivotally attached to the wings, one of said end convolutions of each element being arranged to gyrate in a transverse plane relatively to the axis of said shaft and the opposite end convolutions positioned to act in planes substantially parallel with the axis of said shaft when the ends are secured to the wings, said intermediate convolutions of the elements being free and unattached and located in different radial planes substantially extending through axes of the pivotal connections.

2. A mixing device including, a rotatable shaft having an end for engaging the bottom of a vessel and provided with laterally extending wings

provided with openings therethrough, and flexible agitating elements each including a helical wire-like form normally consisting of a series of coaxial convolutions with the terminals of the end convolutions provided with hooks brought together and pivotally engaged in said openings of the wings, one of said end convolutions of each element being arranged to gyrate in a transverse plane relatively to the axis of said shaft and the opposite end convolutions positioned to act in planes substantially parallel with the axis of said shaft when the hooks are engaged in said openings, said intermediate convolutions of the elements being free and unattached to said shaft and located in different radial planes substantially extending through the axes of said openings, said intermediate convolutions being of larger diameter than the end convolutions to provide variable gyration range with respect to the axis of the shaft.

3. A mixing device including, a rotatable shaft having an end adapted to engage the bottom of a vessel, flexible agitating elements each including a helical wire-like form normally consisting of a series of coaxial convolutions with the terminals of the end convolutions brought together, and means pivotally connecting said terminal ends to said shaft adjacent said end, one of said end convolutions of each element being arranged in a transverse plane relatively to the axis of said shaft and adapted to sweep in parallel contact with the bottom of the vessel and the other end convolutions being positioned to act in planes substantially parallel with the axis of said shaft when said terminals are engaged by said pivotal connecting means, said intermediate convolutions of the elements being free and unattached and located in different radial planes substantially extending through said pivotal connections.

4. A mixing device including, a rotatable shaft having an end adapted to engage the bottom of a vessel and provided with a flattened portion above said end having spaced openings therein, and flexible agitating elements each including a helical wire-like form normally consisting of a series of coaxial convolutions with the terminals of the end convolutions provided with hooks brought together and pivotally engaged in said openings of the flattened portion, one of said end convolutions of each element being arranged in a transverse plane relatively to the axis of said shaft and adapted to sweep in parallel contact with the bottom of the vessel and the other end convolutions positioned to act in planes substantially parallel with the axis of said shaft when the hooks are engaged in said openings, said intermediate convolutions of the elements being free and unattached and located in different radial planes substantially extending through said openings.

5. A mixing device including, a rotatable shaft having one end adapted to engage the bottom of a container, flexible agitating elements each including a helical wire-like form comprising a series of convolutions with their centers arranged on arcs in a plane parallel with the axis of the shaft, and means pivotally connecting the end-most convolutions of each element to said shaft, said intermediate convolutions of the elements being free and unattached and located in different radial planes substantially extending through the axes of the pivotal connections.

JOSEPH H. WITTMANN.
